UNITED STATES PATENT OFFICE.

HARRY NEGBAUR, OF NEW YORK, N. Y., ASSIGNOR TO E & J BASS, INCORPORATED, A CORPORATION OF NEW YORK.

DESIGN FOR A COMBINED BASE AND BODY FOR CANDLESTICKS OR ANALOGOUS ARTICLES.

Application filed October 23, 1923. Serial No. 7,576. Term of patent 3½ years.

To all whom it may concern:

Be it known that I, HARRY NEGBAUR, a citizen of the United States, and a resident of the city, county, and State of New York, have invented a new, original, and ornamental Design for Combined Base and Body for Candlesticks or Analogous Articles, of which the following is a specification, reference being had to the accompanying drawing, forming a part hereof.

The drawing shows in full lines a perspec-

tive view of the design as applied to the combined base and body for candlesticks or analogous articles.

I claim:

The ornamental design for a combined base and body for candlesticks or analogous articles substantially as shown.

HARRY NEGBAUR.
